CLAIM

I claim the ornamental design for a one burner cooker, as shown and described.

DESCRIPTION

FIG. 1 is a front and left-side perspective view of a one burner cooker showing my new design;

FIG. 2 is a rear and left-side perspective view thereof;

FIG. 3 is an exploded perspective view thereof;

FIG. 4 is a top plan view thereof;

FIG. 5 is a front elevational view thereof;

FIG. 6 is a rear elevational view thereof;

FIG. 7 is a left side elevational view thereof; and,

FIG. 8 is a right side elevational view thereof.

One burner cooker for indoor and outdoor cooking.

1 Claim, 8 Drawing SheetsFIG.1.

FIG.2.

FIG.3.

FIG. 4.

FIG.5.

FIG.6.
